W. PATTON

ADJUSTABLE LEVEL AND PLUMB DEVICE

Filed Feb. 4, 1927

Inventor
William Patton
by J. Daniel Stuwe
Attorney

UNITED STATES PATENT OFFICE.

WILLIAM PATTON, OF CHICAGO, ILLINOIS.

ADJUSTABLE LEVEL AND PLUMB DEVICE.

Application filed February 4, 1927. Serial No. 165,773.

My invention pertains to an adjustable level and plumb device; and the principal object of this invention is to provide a level device which is adapted for use for all types of construction work, and more particularly for carpentry, masonry, chimney, and sewer work, and all similar construction work; and which level device requires only one graduated member on the level bar, and only one bulb member to co-operate with said graduated member, said bulb member being arranged to be adjusted and fastened at any desired position or degree on the graduated member, so that the same will function and operate accurately while the level bar is used either in a vertical position, a horizontal position, or at any angle or slant. Another object is to arrange the construction so that the bulb member may be conveniently detached from the device and carried in the pocket or locked away in a small space, between the usual working hours, so as to prevent accidental breaking of the bulb in the level device or stealing of the entire device. A further object is to make the entire bulb member conveniently removable from the device, and also the spirit bulb conveniently removable from the member and replaceable therein.

These and other objects and advantages are attained with my invention, as will become apparent from the following disclosure, comprising the drawing, in which,

Fig. 1 is a side view of a level device embodying my invention, and shown in operation in a slanting or inclined position;

Fig. 2 is an enlarged view, showing my invention in its preferred form of construction;

Fig. 3 is a cross-section, taken on line 3—3 of Fig. 2;

Fig. 4 is a perspective view of the pivot for the bulb member;

Fig. 5 is a side elevation of the bulb member, which is conveniently detachable from the pivot and the entire level device, and again attachable thereon; and

Fig. 6 is an enlarged cross-sectional view, taken on line 6—6 of Fig. 2.

In the drawing I have shown the preferred form of construction embodying my invention, and have provided a level bar 10 with a bore or opening 11 therein. At one end of said bore, and preferably even with one face of the bar, I mount a graduated annular member or ring 12, as with screws

13, and having graduated marks 14 arranged in a complete circle thereon and in the form of degrees. On the actual article, in practice, said marks are graduated down to a fraction of a degree. Notches or slots 15 are also provided at diametrically opposite parts of said ring.

I also provide pivot means, preferably including a circular member or plate 16 mounted, as with screws 17, at the end of bore 11 and the face of bar 10 opposite ring 12, and preferably place said plate even with said face, as shown in the drawing. A pivot pin or shaft 18 extends up from said plate into the center of the bore.

In conjunction with the above described elements, I provide one bulb device or bulb member and therewith make the level device operative for use at any angle or inclination as well as vertical and horizontal, and this bulb member preferably includes an oblong frame 20 having a transverse sleeve or collar 21 thereon to embrace and turn or rotate on pivot pin 18. A pointer or 80 finger 22 on one end of said member moves over the graduation marks 14, and an ear 23 at the other end of said member is provided with a set screw 24, for fastening the member in position with the pointer at the proper index position or degree on the ring. Lugs 25 are provided at the ends of member 20, beneath elements 22 and 23, and are movable through notches 15, thus permitting 85 convenient mounting of the bulb member on the level device and also convenient removal therefrom to enable it to be carried away in the pocket or stored away in a small space.

These lugs normally engage the under side of ring 12 while the pointer and ear engage the upper side, thus ordinarily retaining the bulb member in its set position, but the set screw 24 is additionally provided to hold the member positively in the particular index position or at the exact degree required. 90

The bulb itself or spirit bulb is also removably mounted in the frame, so as to be readily detached and replaced if necessary, and this is done by providing a tube or case 26 with the bubble tube or glass bulb 27 105 therein showing through the top slot 28, and this spirit bulb is removably fastened by screws 29 in the frame engaging the ends of said case 26.

It is apparent from the above disclosure 110 that I have provided a level device in which the bulb member may be readily adjusted

and set at any desired position or degree of the entire circle, and that the level device functions accurately whether used vertically, horizontally, or at any angle or degree of 5 inclination; and also that the bulb member may be conveniently detached and attached to the level device, to permit removing and carrying it for safe keeping. It is evident that with this construction only one level 10 device and equipped with only one bulb member, will serve the purpose of a plurality of the ordinary level devices, and especially of the level device with several bulb members set at right-angles therein.

15 What I claim as my invention and desire to secure by Letters Patent is:

1. A level device comprising a bar having a bore and a notched graduated ring on one side thereof, a member with pivot means in 20 said bore opposite said ring, a bulb member having pivot means turning on and removable from the first pivot means, a pointer on the bulb member, lugs on said bulb member

to be moved through the notches on the ring for readily attaching or detaching said 25 member from the ring and bar, and means for positively retaining said pointer at any degree on the graduated means.

2. A level device comprising a bar having a bore and a ring graduated in degrees 30 around said bore, said ring having notches, means with a pivot element in said bore, a bulb member having a central pivot element turning on the first named pivot element, a pointer at one end of said member, lugs on 35 said member movable through said notches for readily attaching or detaching said member from the ring and bar, said member including a bulb removably mounted therein, and an ear on said member having means 40 for fastening it on the ring with the pointer at any desired degree.

In testimony whereof, I have signed my name to this specification.

WILLIAM PATTON.
